UNITED STATES PATENT OFFICE.

ARTHUR L. HOWE, OF METHUEN, MASSACHUSETTS, ASSIGNOR OF ONE-FOURTH TO WILLARD R. WHITNEY, OF METHUEN, MASSACHUSETTS, AND ONE-FOURTH TO JOHN W. SMITH, ADMINISTRATOR OF WILLIAM SMITH, DECEASED, LATE OF LAWRENCE, MASSACHUSETTS.

ADVERTISING APPARATUS.

1,003,745.

Specification of Letters Patent. Patented Sept. 19, 1911.

Application filed October 27, 1908. Serial No. 459,732.

To all whom it may concern:

Be it known that I, ARTHUR L. HOWE, of Methuen, county of Essex, State of Massachusetts, have invented an Improvement in 5 Advertising Apparatus, of which the following is a specification.

This invention particularly relates to an advertising device which is arranged in the form of an opera-house and in which advertising matter is automatically displayed, and has for its object to provide an advertising device of the above character, which is wholly automatic, and in which an advertising strip is automatically conducted from 10 one roll to another across the stage opening while the curtain of the stage is raised, and is conducted in the opposite direction when the curtain is lowered, the automatic raising and lowering of the curtain and the automatic winding and unwinding of the advertising strip being carried on indefinitely, so 15 long as the driving mechanism is actuated.

For a complete understanding of my invention, and the means which I employ in carrying out the above objects, reference is 20 made to the accompanying drawing, in which,

Figure 1 is a front elevation of a miniature opera-house, provided with my invention. Fig. 2 is a vertical section on the line 2-2 of Fig. 3, showing the main actuating mechanism. Fig. 3 is a side elevation with the outside casing partly broken away. Fig. 4 is an enlarged detail sectional view taken 25 on the line 4-4 of Fig. 3. Figs. 5 to 10 are detail views of the automatic switch-operating mechanism. Fig. 11 is a diagrammatical view of the circuits.

In Fig. 1, a miniature opera-house *a* is 30 indicated in which may be placed various figures which may be automatically operated in any well-known manner, such means forming no part of my invention. Foot-lights *a'* and box-lights *a''* may be provided, 35 which are alternately lighted and extinguished, as hereafter described.

A drop curtain *b*, having a weighted bottom *b'*, is provided, said curtain being adapted to be wound upon a roll *c* to raise 40 the same. Said roll *c* is mounted upon a shaft *c'* and said shaft is rotatably held in bearings *c''*, at each end of said roll. A friction clutch mechanism is provided for said

roll, comprising a loose member *d*, which is 45 rotatably mounted on shaft *c'* at one end and a fast member *d'*, which is splined on 50 said shaft. An operating lever *e* is pivotally mounted at *e'* on the frame, said lever being arranged to engage said clutch member *d'* at one end, and to move it into operative relation with the member *d*, while its opposite end constitutes the armature of an electromagnet *f*, so that when said magnet is energized the clutch will be operated.

A pair of rolls *g* and *h* are respectively 55 mounted below and above the stage opening, and the advertising strip *i* is adapted to be wound on both rolls and to be driven from one to the other across the stage opening when said rolls are correspondingly rotated. 60 The lower roll *g* is mounted on a shaft *g'*, which is journaled in bearings *g''* and said shaft is provided with a friction clutch mechanism at one end which comprises a loose member *k*, which is rotatably mounted 65 on said shaft, and a fixed member *k'* which is splined thereon. The upper roll *h* is mounted on a shaft *h'* which is journaled in bearings *h''*, and said shaft is likewise 70 provided with a friction clutch mechanism which comprises a loose member *j* and a fixed member *j'* which is splined thereon.

A main shaft *m* is provided, upon which a motor *m'*, indicated in dotted lines in Fig. 2, may be mounted, and an upright shaft *n*, 75 mounted in bearings *n''*, is adapted to be driven by said main shaft *m* through a worm-gear *n'* and a worm *m''*, so that when said motor is in operation, said shaft *n* will be constantly rotated in one direction. The 80 loose clutch member *j* is provided with a worm gear *j''*, and shaft *n* is provided at its upper end with a right hand worm *n''*, which meshes therewith, and the member *k* is also provided with a worm gear *k''* which is in 85 mesh with a left hand worm *n''* on the lower end of shaft *n*. The loose members *j* and *d* are each provided with a peripheral gear, which is arranged in mesh with a loose gear *o*, so that said loose members *d* and *j* will 90 be constantly driven in one direction while the member *k* will be constantly driven in the opposite direction.

An operating lever *p* is pivotally mounted 95 at *p'* on the casing and the opposite arms of said levers are adapted to be arranged to act

as the armatures of a pair of electro-magnets p^2 and p^3 . The upper end of said lever p is adapted to engage the clutch member j' and move it into operative relation with member j when said magnet p^2 is energized, while the lower end of said lever is arranged to engage member k' and to move the same into operative relation with member k when the magnet p^3 is energized.

10 An automatically operated switch is provided, which comprises an arm q , which is adapted to swing between two adjustably mounted stops q' and q'' . One wire terminal y is connected to said arm q and a contact spring q^3 is mounted on said arm in position to engage either of a pair of contact plates q^4 and q^5 , according to the position to which said lever is thrown.

15 The opposite end of the shaft h' from the clutch j, j' is provided with a worm h^3 which is adapted to mesh with a worm gear r , mounted on a shaft r' directly beneath the same, and a pair of spring arms s and s' are adjustably connected to said worm gear r , by means of washers s^2, s^3 , on which said arms are respectively mounted, said washers being mounted on the shaft r' and being adapted to be clamped against the worm wheel r by means of a nut r^2 , to hold them 25 in any position to which they may be adjusted. Said spring arms s and s' are shown, for example, as set in diametrically opposite positions, and, when shaft r' is rotated, they are adapted and arranged to engage the pins q' and q'' respectively, and the adjacent sides of the arm q , as hereafter explained.

20 A brake mechanism for the drop curtain is provided which comprises a spring arm t , which is pivotally mounted at t' on the casing, in such position that one end thereof, may bear in a screw thread c^3 on the left hand end of the curtain shaft c' , so that, as said shaft is rotated to lower the curtain, 25 said spring arm t will be swung inwardly toward roll b . A stop screw u is mounted in the casing at the inner side of said arm t , adjacent the pivot t' , and in position to be engaged by said arm as it is swung inwardly.

30 An opening t^o in the arm t , of smaller diameter than the head of said screw, permits of ready adjustment of the latter with a screw driver. A spring finger t^3 is mounted on arm t in position to engage a projection c^4 on the end of the shaft c' when said arm t is moved to its extreme inward position.

35 A single tooth ratchet v is mounted on the end of the shaft c' adjacent the clutch-member d' , and a spring pawl w is mounted on the lever p adjacent said upper end, said pawl having a transversely extending end portion w' for engaging the tooth of said ratchet.

40 A spring contact finger b^2 is supported on the frame-work directly beneath the roll b

in position to bear on the upper side of a contact plate b^3 , likewise supported, and a finger b^4 is provided on the inner side of the curtain which is adapted to engage said finger b^2 and lift the same out of contact with the plate b^3 as the curtain is raised to its fullest extent.

45 As shown in the diagram in Fig. 11, the circuit wire x leads to the main switch z and a branch x' therefrom is extended about the electro-magnet p^2 and then on through the stage foot-lights a' to the contact plate q^5 . Another branch x^2 is extended about the magnet f and connected to the plate b^2 , the plate b^2 being connected to the plate q^5 . A third branch x^3 passes about the electro-magnet p^3 and on through the box-lights a^2 , and is connected to the contact plate q^4 .

50 Assuming that the switch q is in the position of the diagram of Fig. 11, so that arm q is in contact with plate q^5 , and that the curtain b is down, and the shaft n is being constantly rotated by the motor, the magnets p^2 and f will be energized causing the clutch member j' to be forced against the member j and the member d' to be forced against the member d , so that the roll h is rotated to wind the strip i thereon, the roll g being free to rotate to permit the strip to be unwound therefrom, and the roll c is rotated to raise the curtain b . As the curtain b is raised, and after it has been raised to the desired extent, the finger b^4 on the lower end of the curtain will engage the switch finger b^2 and break the circuit through the magnet f , so that clutch d, d' will be released and further winding movement of the roll c will not be caused.

55 As the curtain is weighted the pawl w and ratchet v are provided to hold the curtain in its raised position, the movement of lever p to operate clutch member j carrying the end portion w' of the pawl onto the ratchet v , so that it bears thereon during the entire time that the curtain is being raised, and, when the clutch d' is released, therefore, the tooth of the ratchet engages said pawl locking the curtain in raised position during the remainder of the time that the strip i is being wound onto the upper roll h . As the strip i is wound on the roll h the worm wheel r will be rotated in the direction of the arrow of Fig. 2, causing the spring finger s to be swung downwardly, so that it finally engages the stop pin q' , as shown in Fig. 6, and, as the strip becomes nearly wound upon the roll h , the worm wheel r will be turned so that the finger s will be placed under a strong tension, as indicated in said Fig. 6, until it is finally bent sufficiently to permit it to slip by the pin q' and strike the switch arm q . The tension under which the finger has been placed will be sufficient to throw the arm q quickly to its opposite position against the stop pin q'' , and into en-

gagement with the other contact plate q^4 . The result will be that the circuit through the magnet p^2 will be broken and the circuit through the magnet p^3 will be made. This will cause the lever p to be thrown to its opposite position, permitting the clutch members j, j' to become disengaged and causing the clutch members k, k' to become engaged. This movement of the lever p 10 also draws the pawl w out of engagement with the ratchet v , so that the curtain b will be liberated and the curtain will become unrolled by reason of its weighted bottom strip b' . During the winding of the curtain 15 on the roll c , the arm t will be carried to the extreme outer end of the threaded portion c^3 , and as the curtain is unwound said arm t will be carried inwardly or toward the roll b by said threaded portion, causing said 20 arm to be pressed against the screw u and the friction of the arm on the thread to be increased as it approaches the inner end of the thread c^3 . When the curtain is fully 25 down the finger t^3 will have moved in far enough to engage the stop pin c^4 preventing further rotation of said roll c . The lowering of the curtain is thus gradually arrested and finally stopped.

When the clutch members k, k' are held 30 in operative relation by lever p the roll g will be driven and the strip i will be wound thereon, and as the shaft k' will then be rotated in the opposite direction, the worm gear r will be driven in the opposite 35 direction from that indicated by the arrow in Fig. 2, and the arm s' will be thrown until it bears against the pin q^2 , and, when the strip is nearly wound on roll g , said finger s' will slip from said pin and engage the 40 switch arm q and throw it into the initial position, so that the operation above described will be repeated. The advertising

strip will thus be exposed to view when it is being carried in one direction, as the curtain is lifted at the beginning of the movement, and will be obscured from view as soon as the movement is reversed to wind the strip back as the curtain will then be immediately lowered.

The foot-lights a' will be lighted when 50 the curtain is raised and the box-lights will be extinguished, while the opposite will take place when the curtain is lowered.

Having thus described my invention, what I claim as new and desire to secure by Letters Patent is:—

1. In combination with a roll having a curtain arranged to be wound thereon and having gravity actuated means for unwinding the same, means for holding the roll in 60 wound position, and a brake device disposed to engage the roll with increasing force as the curtain is unwound, substantially as described.

2. A device of the character described 65 comprising a roll having a curtain adapted to be wound thereon, a constantly driven shaft, clutch-mechanism for connecting said shaft and said roll to wind up the curtain, an engaging device on the curtain for releasing said clutch mechanism when the curtain is lifted, a locking device for holding the curtain in raised position and means for automatically releasing said locking device 70 to permit the curtain to unwind, substantially as described.

In testimony whereof, I have signed my name to this specification, in the presence of two subscribing witnesses.

ARTHUR L. HOWE.
